UNITED STATES PATENT OFFICE.

GAY H. BUTLER, OF ATLANTA, GEORGIA.

STEAM DRIER.

Application filed August 26, 1925. Serial No. 52,664.

This invention relates to a steam drier construction.

A prime desideratum is to provide an apparatus of this kind which is particularly applicable to a brick drier or the like to generally simplify, render more efficient and reduce the cost of operation of the same.

Specifically an aim is to provide a structure of this type in units capable of use singly or in a battery, devoid of flues therethrough, whereby special front or rear ends are unnecessary, so that the front wall may be formed by a continuation of the masonry of the firebox, and the space arched by the unit or units may communicate directly or with the discharge flue for the firebox.

Additional objects and advantages will become apparent if not later specifically mentioned, from a consideration of the description following taken in connection with accompanying drawings illustrating an operative embodiment.

In said drawings:—

Figure 1 is a view of the apparatus in front elevation, but partially installed to disclose details;

Figure 2 is a plan of one of the drier units, partly broken away and in section;

Figure 3 is a side elevation of one of the drier units, and

Figure 4 is a perspective view suggesting a battery of the drier units connected in operative relation.

Referring specifically to the drawings, wherein like reference characters designate like or similar parts, drier units are shown at 10 and each unit is designed so that it may be made in a single metallic casting. Each unit 10 is similar, of arch shape as shown in that it comprises spaced parallel arched walls of substantially equal length joined at their edges by end and bottom walls, has an interiorly unobstructed water space, attaching lugs 11 integral with the unit, a plurality of openings 12 through the end walls thereof and an opening 13 through the top.

One or more units 10 may be used in an installation. When one unit is employed, openings or apertures 12 at both end walls have suitable plugs or closures 14 screwed or otherwise fastened therein, as shown in Figures 2 and 3. Water is supplied to the unit or units as through a pipe *a* connected in one of the lowermost plugs 14 at the front of the unit and the return line *b* for

condensation is connected at the opposite end in the adjacent lowermost plugs 14. A pipe 15 is screwed into the opening 13 through which steam under appropriate control may be taken from the unit. Said pipe 15 may extend to coils or the like in drier tunnels for drying purposes. Obviously the unit, as in Figure 1, may be equipped with accessories such as steam or pressure gage 16, and a water gage 17 arranged in communication with the water space of the unit by pipes 18.

Said unit 10 is used in connection with a furnace 19 as in Figure 1. Furnace 19 has upright walls of masonry at 20 on which the section 10 rests and to which it is cemented and anchored, as by means of bolts 21 passed through the lugs 11. As a result, the unit crowns the combustion chamber or firebox 22. The fuel door of said furnace is shown at 23 and below the same is an ash-pit door 24. The front wall 20 covers the entire front of unit 10 and the products of combustion from the furnace discharge from the combustion chamber directly into a chimney or smoke flue to which the unit is directly fastened and anchored by cement and the aforesaid bolts 21.

The unit is arranged under a drying tunnel in a kiln so that the bricks placed therein, usually on trucks, will be subjected to the drying action of the heat radiating from the drier unit through generation of steam in the latter when fire is maintained in furnace 19. Preferably a steam pressure of twenty-five pounds is maintained in the unit 10.

About the openings 12 and 13, each unit is preferably reinforced by bosses 26 and 27.

Said units 10 may be used in battery form instead of singly. Referring to Figure 4, in this connection, three units 10 have been so shown although the number employed is optional. These units 10 are mounted in a furnace 19 similarly to the single unit. In the present instance, openings 12 of the facing ends of the units are not plugged but remain open and aligned, and the units are clamped together water-tight by bolts 28 passed through adjacent ears 11. Plugs 14 are used for the openings 12 only at the free end walls of the outer units 10. Also, branch pipes 29 (in lieu of pipe 15) are detachably threaded into the openings 13 and in turn threaded to a pipe 30, which functions similarly to the pipe 15. Anchor

bolts may also be used in the front and rear series of lugs 11 to engage the front wall of the furnace and the chimney.

In both arrangements, a fire in the furnace 19 causes steam to be generated within the units 10, due to the presence of water supplied through pipes into plugs 14 in rear end of section, say, to the extent of twenty-five pounds pressure. The heat radiating from the units is imparted to and dries the bricks or other materials in the associated drying tunnel or the like through steam pipes and coils. All products of combustion pass directly from the chamber or space 22 into the discharge flue. In both arrangements, the bolts and pipe connections are readily displaceable to enable removal, substitution or repair of a unit.

Various changes may be resorted to within the spirit and scope of the invention as defined by appended claims.

I claim:

1. In a boiler construction, an integral casting having two spaced substantially par-

allel walls of arch-shape and of substantially equal length joined at their edges by end and bottom walls to provide a water chamber, said casting being of such dimensions as to enable its use as a boiler in itself, the end walls being provided with apertures adapted to be selectively plugged, or arranged in communication with other boiler parts.

2. In a boiler construction, an integral casting having two spaced substantially parallel walls of arch-shape and of substantially equal length joined at their edges by end and bottom walls to provide a water chamber, said casting being of such dimensions as to enable its use as a boiler in itself, the end walls being provided with apertures adapted to be selectively plugged, or arranged in communication with other boiler parts, and outwardly extending attaching lugs at each end of the casting disposed substantially in longitudinal alignment.

GAY H. BUTLER.
